United States Patent Office

Des. 222,713
Patented Dec. 14, 1971

222,713

WESTERN STORE BUILDING

Charles C. Hicks, Goodlettsville, Tenn., assignor to Lynn's
Loretta Western Stores, Inc., Hermitage, Tenn.

Filed Nov. 25, 1970, Ser. No. 26,162

Term of patent 14 years

Int. Cl. D25—03

U.S. Cl. D13—1

Fig. 1

Fig. 2

Fig. 3

FIG. 1 is a front elevational view of the western store building, made in accordance with my invention;

FIG. 2 is a right-side elevational view with a middle uniform portion removed; and

FIG. 3 is a reduced rear elevation.

I claim:

The ornamental design for a western store building, as shown.
